UNITED STATES PATENT OFFICE.

LAWRENCE L. KAHN, OF SAN FRANCISCO, CALIFORNIA.

MEANS FOR PRESERVING FOOD.

1,256,495.

Specification of Letters Patent. Patented Feb. 12, 1918.

Application filed August 18, 1917. Serial No. 186,831.

To all whom it may concern:

Be it known that I, LAWRENCE L. KAHN, of No. 6 Second avenue, in the city of San Francisco, county of San Francisco, and 5 State of California, have invented a certain new, useful, and Improved Means for Preserving Food.

My invention relates to improvements in methods of and means for preserving food 10 and the object of my invention is to provide a method which will effectually prevent the great waste which occurs with the present most approved methods of preserving meats, vegetables, etc., and which shall result in 15 the practically perfect preservation of such materials that are subject to rapid decay, for any desired length of time and in any climate of either extreme heat or extreme cold.

20 A further object of my invention is to provide means for practically carrying my improved method into effect.

My invention consists in a method of preserving meats, vegetables, etc., which comprises the inclosing of the material in a metal can, such as the ordinary tin can, applying heat to the can in the usual manner, thereby expelling the air and heating the contents to the proper degree in accordance 25 with the usual practice, but before placing the material in the can, and while the same is still open, I place a lining in the can comprising a thin sheet of amorphous material 30 of vegetable origin which is impervious to water and germ proof, such as celluloid. Then I place the material to be preserved in the can within the lining and then I cover the contents with a sheet of the material of 35 which the lining is made, and then I hermetically seal the metal cover on the can and proceed in the usual manner to heat the can and its contents, and I finally hermetically seal the can itself.

My improvement consists in the inclosing 45 of the material to be preserved in a germ proof lining which is impervious to water, arranged between the contents and the inner surface of the metallic container, and which effectually prevents the contamination of 50 the contents by contact with the metallic container.

My improved means for preserving food 55 consists of a hermetically sealed metallic container lined with a relatively thin sheet of amorphous material, such as celluloid, and which effectually prevents the contact-

ing of the food placed within the lining with the inner surface of the metal container.

My invention also consists in the use of a 60 separate lining in the metallic container, which lining is impregnated with camphor to the end that the lining is practically germ proof, or which tends to destroy or kill any germs which might be deposited upon its 65 surface.

It has long been known that the preservation of foods, and particularly meats and meat products, under the methods now in use, is more or less doubtful. In fact, such 70 products are only usually guaranteed to stay in proper condition but a few months, with the consequence that it frequently occurs as a matter of history that many thousand cans, or may be hundreds of tons, of such 75 preserved meat become unfit for human consumption and are a total loss to the owners thereof. Furthermore, it often occurs that such spoiled meats are inadvertently eaten with the possible consequence of sickness 80 and frequently the death of those partaking.

All of these losses and unwanted results are positively eliminated by the use of my improved method of and means for preserving food, for the reason that the main source 85 of difficulty lies in the contacting of the food contents with the metallic or tin container. It is not sufficient to line the can with paper, such as tissue paper or paraffin, otherwise known as sanitary paper, for such 90 linings are not germ proof, and in that sense they do not prevent the practical contacting of the contents with the metallic container. Although the escape of the liquid contents through the cracks between the parts of the 95 lining into contact with the container does not deleteriously affect the contents, I sometimes so form the lining that I substantially prevent such leakage of the contents, and in other cases I form the lining so as to reduce 100 such cracks or joints to a minimum.

My invention will be more readily understood by reference to the accompanying drawing forming a part of this specification and in which I have illustrated my improved means for preserving food, and which sufficiently illustrates my improved method to give a complete understanding thereof to one skilled in the art.

In said drawing: 110

Figure 1 is a vertical section of a container provided with a lining made in ac-

cordance with my invention, and by means of which I am enabled best to carry out my improved method of preserving food;

Fig. 2 is a horizontal sectional view of 5 the container on the line 2—2 of Fig. 1; and

Figs. 3 and 4 are sectional views similar to Fig. 1 showing modified forms of lining.

In carrying out my improved means of preserving food as explained hereinbefore,

10 I proceed in the usual manner of preserving food, vegetables, meats, etc., in metallic or tin cans, except that I first line the container with a germ proof and water proof lining, which is of such material that it will effect- 15 ually prevent the passage of germs from the metallic container to the food, which will effectually prevent the formation of any de- 20 structive material caused by any chemical action which may be set up between the food or meat acids and the metal container, and which will not adhere to the surface of the metal. I have discovered that thin celluloid has all the necessary qualities. Its 25 nature is such that though germs may be de- posited upon it it does not serve to propo- 30 gate them but rather to destroy them, the slight trace of camphor therein effectually preventing untoward effects.

It is quite possible that some other ma- 35 terial equally efficacious may be discovered, and I do not confine or limit my invention to the use of celluloid, but one novelty in my invention resides in the discovery that a thin sheet of celluloid, when used as a 40 lining, will effectually prevent the destruction of the contents of a metallic container in any climate either extremely hot or ex- 45 tremely cold, and for an indefinitely long time

40 In said drawing A is a metallic, prefer- ably tin, container, having a body B and a cover C. At the time the contents are placed in the can the cover C is not on the can, in other words, the top is open. I first place 45 the lining D within and in contact with the side walls of the can, which may be of cir- 50 cular cross section, or any other suitable shape. This lining may consist of a strip of the celluloid, arranged with its ends in overlapping contact, as at E. Then I place 55 a disk F of the sheet material, which fits snugly within the lining in the bottom of the container; then in preserving the food I place the food in the container, filling it full. After the container has been filled I place a second disk G, similar to the disk F upon the top of the contained food, and then I hermetically seal the cover C upon the body B. The cover is provided with 60 the usual hole or opening for the escape of the steam or air during the heating process, and I then subject the can and its contents to the action of heat of the proper degree and a suitable time, according to the nature 65 of the contents, and which are well known

to those versed in the art. When the can and its contents have been heated to the proper degree for a sufficient length of time I hermetically seal or close the hole in the cover of the can in the usual manner with 70 a drop of solder.

In the preservation of some foods, particularly those containing a large proportion of liquid, such as vegetables or fruits, I sometimes prefer to modify the lining as 75 shown in Figs. 3 or 4. The lining in Fig. 3 consists of the bottom disk H, having an upturned flange, J, within which the lower end of the lining of the vertical wall fits. The top or cover K is provided with a simi- 80 lar flange L, which preferably fits within the upper end of the vertical lining.

In Fig. 4 I have shown a lining of but two pieces, the bottom and vertical wall being formed or pressed out of a single piece M, 85 and forming a cup-like container without a joint, and the top being preferably of the form K as shown in Fig. 3, having a flange L which fits within the upper end of the side wall.

90 In all forms of my improved container I provide a lining made of germ proof material which is impervious to water and all weak acids or alkalis which might be or form in foods, and which lining effectually 95 prevents the food contents of the container from contacting directly or indirectly with the inner wall of the container.

Having thus described my invention I claim as new and desire to secure by Letters 100 Patent:

1. A closed vessel in which to preserve food, comprising a metallic container, hav- 105 ing a lining contacting with the inner sur- face thereof, and adapted to completely en- compass the food in said container, said lining comprising a thin sheet of amorphous material of vegetable origin which is im- 110 pervious to water and such acids and alkalis as might be found in the food or food prod- 115 ucts, and is germ proof.

2. A closed vessel in which to preserve food, comprising a metallic container, hav- 120 ing a separable lining contacting with the inner surface thereof, and adapted to com- pletely encompass the food in said container, 111 said lining being composed of a thin sheet of amorphous material which is impervious to the liquors in which foods are ordinarily preserved, and is germ proof.

3. A closed vessel in which to preserve food, comprising a metallic container, hav- 125 ing a lining contacting with the inner sur- face thereof, and arranged to completely encompass the food, said lining comprising a thin sheet of celluloid adapted to com- pletely inclose the food contents of the vessel.

4. A closed vessel in which to preserve food, comprising a metallic container, hav- 130

ing a lining composed of sheet material containing a small percentage of camphor adapted to completely inclose the food contents of the vessel and to prevent the contacting thereof with the inner surface of the latter.

5. A closed vessel in which to preserve food, comprising a metallic container, having a separate lining within the same, and 10 arranged to encompass the food, said lining comprising a sheet of material of vegetable origin, which is germ-proof and impervious to water, inclosing the food contents and preventing the direct contact thereof with 15 the inner surface of the vessel.

6. The herein described improvement in the art of food preservation, comprising a metallic can or container, and a lining of sheet celluloid covering the inner surface of

the can and adapted to envelop food contained within the can.

7. A vessel in which to preserve food, comprising a metallic container, and a celluloid lining therein adapted to prevent the contacting of the food contained in the vessel with the inner surface thereof.

8. A metallic food container, and a celluloid lining therein.

9. A tin can in which to preserve food, and a celluloid lining therein adapted to 30 prevent the contacting of food contained in the can with the inner surface thereof.

In testimony whereof, I have hereunto set my hand this 15th day of August, 1917, in the presence of one subscribing witness. 35

LAWRENCE L. KAHN.
